UNITED STATES PATENT OFFICE.

LUCIEN I. YEOMANS, OF CHICAGO, ILLINOIS, ASSIGNOR TO PIONEER PRODUCTION COMPANY, OF CHICAGO, ILLINOIS, A CORPORATION OF ILLINOIS.

SHAFTING CLEANER.

Application filed November 5, 1920. Serial No. 421,871.

To all whom it may concern:

Be it known that I, LUCIEN I. YEOMANS, a citizen of the United States, residing at Chicago, in the county of Cook and State of Illinois, have invented certain new and useful Improvements in Shafting Cleaners, of which the following is a specification.

The invention relates to shafting cleaners and has for its object the provision of means for automatically cleaning power transmission or other revolving shafting.

It is the common practice in hanging line shafting for power transmission to suspend the shafting from overhead building structure where it is removed from ready accessibility. Its usual location makes manual cleaning inconvenient and costly, and without cleaning, the shafting accumulates an unsightly and unsanitary deposit of dirt upon its revolving surface. It is the primary object of this invention to provide means for automatically preventing such accumulation of dirt on the shafting.

A further object is to provide such means in a simple construction, cheap to manufacture and readily assembled on any shafting, and continuous and noiseless in its operation. I attain these objects by constructing an annular device of narrow cross section which may be assembled about the shaft and which is adapted to roll upon the rotating surface of the shaft. The inner diameter of the device being greater than the diameter of the shaft, the device when assembled about a horizontally hung shaft is in contact therewith at one point only. A slight current of air, irregularity in the surface of the rotating shaft or contact with a hanger or pulley will deflect the device from a perpendicular relation and cause it to travel longitudinally of the shaft, describing an irregular spiral path. By providing a recess in the inner periphery of the device and a filling therein of suitable material, such as felt, I utilize the longitudinal movement of my device to accomplish a sweeping effect upon the surface of the shaft. The soft material also prevents any objectionable noise arising from its operation. The maximum movement of the device is limited by the shafting hangers or pulleys. Within those limits it is in constant operation when the shaft is revolving.

In the accompanying drawings I have illustrated a preferred embodiment of my in-

vention, but it is to be understood that in the interpretation of the appended claims they are not to be limited to the precise construction or arrangement set forth, except as may be necessitated by the state of the prior art.

Fig. 1 is a side view of the device illustrated as assembled in position about a shaft. Fig. 2 is a cross sectional view taken along the line 2—2 of Fig. 1 and indicates the construction for carrying the felt filling. Fig. 3 is a perspective view of one of the fasteners by which the parts of the device are preferably assembled. Figs. 4 and 5 illustrate modifications of the construction shown in Fig. 2. Fig. 6 illustrates a modified form of fastening means for holding the parts in assembled position.

Referring now to Fig. 1, the numeral 1 indicates in cross section a portion of line shafting on which is mounted my device indicated generally at 2. In my preferred construction, the device comprises two pairs of complementary semi-circular members indicated at 3 and 4, and 5 and 6 respectively, each pair being assembled end to end with its joints overlapping the center portion of the opposite pair. Each member has a transverse slot 7 located near each end and a pair of slots 8 located at its center portion, the slots being so positioned that those of one pair register with the slots of the other pair when assembled. The members are secured in assembled position by means of fasteners 9 of sheet metal formed in the shape of a T, their free ends being inserted through the registered slots and clinched.

Each member is dished along its inner periphery 10 so that when assembled the pairs of members form an annular recess 11 about the inner periphery in which is packed felt, or other fibrous material, extending slightly outward from the recess as at 12 to make contact with the surface of the shafting when in operation. Preferably, the inner edges of the members forming the recess 11 are turned convergently, as at 11a. The inturned edges assure the retention of the fibrous filling packed in the recess, and reduce the bearing surface to a narrow strip which increases the tendency of the cleaner to travel longitudinally of the shaft.

The device being constructed in sections, it may be readily installed by simply assembling the parts about a shaft.

My device also may be constructed in

modified form without the dish in the members, by forming the latter of flat sheet material as indicated by numerals 4^a and 5^a (Fig. 5), and introducing a sheet of felt 12^a or similar material between the members for their entire width, with a margin of the felt protruding from their inner peripheries.

In my preferred embodiment, I have constructed the arcuate members from sheet metal, but I find that good results may be obtained by constructing the members of sheet fibre as illustrated at 4^b and 5^b (Fig. 4), without the intermediate packing of felt. In this embodiment the inner peripheries of the fibre members bear directly upon the surface of the shaft.

I may also dispense with the independent fasteners and secure the members in assembled position as illustrated in Fig. 6 by striking up at the center of each member a pair of integral tongues 13 which engage with and may be clinched through slots 14 in the ends of the complementary pair of members.

It will now be apparent that I have provided a continuously effective means for automatically cleaning shafting, which is simple in construction, cheap to manufacture and noiseless in operation.

I claim as my invention:

1. In a device of the class described, a body portion having an opening through which a shaft is adapted to extend, a fibrous surface surrounding said opening, said surface being adapted for wiping engagement with the shaft to clean the same upon rotation thereof.

2. In a device of the class described, a sectionalized body portion defining an opening through which a shaft is adapted to extend, a fibrous surface surrounding said opening, said surface being adapted for wiping engagement with the shaft to clean the same upon rotation thereof.

3. A shafting cleaner comprising a plurality of segmental elements having arcuate inner peripheries of thin cross section and adapted to be assembled about a substantially horizontal shaft with their said peripheries continuously joined to form a ring of substantially greater inner diameter than said shaft, said ring being adapted to revolve in rolling engagement with the upper surface of said shaft and being capable of swinging away from perpendicular relation to said shaft thereby tending to travel longitudinally thereupon.

4. A device for cleaning shafting comprising, in combination, an annulus adapted to be mounted about a rotary shaft and having its inner diameter greater than that of

said shaft, a radial recess of narrow cross section formed in the inner periphery of said annulus, and a filling of resilient material carried in said recess, said filling having rolling contact with said shaft at one point only and tending to describe an oscillatory spiral path thereon by the deflection of said annulus from perpendicular relation to said shaft.

5. A shafting cleaner comprising a plurality of segmental elements of sheet material having arcuate inner peripheries of like radius and assembled in the form of a laminated ring adapted to freely surround a rotary shaft, a filling of fibrous material secured between the laminations of said ring, and means for detachably securing together said segments and filling.

6. A shafting cleaner comprising a pair of like sectional rings of sheet material detachably secured in concentric relation, the inner opening of said rings being adapted to encircle and be suspended upon a rotary shaft of less diameter, said rings being oppositely dished about their inner peripheries to form an annular recess therebetween, and a filling of fibrous material secured in said recess and extending outwardly therefrom to engage said shaft.

7. A device of the class described comprising overlapping semi-circular sections of like dimensions assembled to form an annulus, said sections having slots to receive fastening devices adapted to detachably secure said sections together.

8. A device for cleaning shafting comprising two pairs of similar elements adapted to be assembled in overlapping relation surrounding a revolving shaft and having the opening for receiving said shaft of substantially greater area than the cross section of the shaft, the ends of each pair of said elements abutting intermediately of the ends of the other pair of elements and each pair having slots formed therein registering with slots formed in the opposite pair, and a plurality of fasteners removably engaging said slots to secure said elements in assembled position.

9. In a device of the class described, a body portion comprising a pair of sectionalized plates defining an opening through which a shaft is adapted to extend, said plates having cooperating slots and tongues for detachably securing them together, and a fibrous surface for wiping engagement with and longitudinal movement along the shaft to clean the same.

In testimony whereof, I have hereunto set my hand.

LUCIEN I. YEOMANS.
